US0D1053376S

(12) **United States Design Patent** (10) **Patent No.:** **US D1,053,376 S**
(45) **Date of Patent:** **** Dec. 3, 2024**

(54) **ATTACHMENT FOR MASSAGE DEVICE**

(71) Applicant: **Therabody, Inc.**, Los Angeles, CA (US)

(72) Inventors: **Jason Wersland**, Los Angeles, CA (US); **Benjamin Nazarian**, Beverly Hills, CA (US); **Jaime Sanchez Solana**, Los Angeles, CA (US); **Danny Zeng**, Shenzhen (CN); **Yano Pang**, Shenzhen (CN); **Sunny Wang**, Dongguan (CN)

(73) Assignee: **Therabody, Inc.**, Los Angeles, CA (US)

(**) Term: **15 Years**

(21) Appl. No.: **29/911,351**

(22) Filed: **Sep. 1, 2023**

(51) LOC (14) Cl. **24-01**

(52) U.S. Cl.

USPC **D24/215**

(58) **Field of Classification Search**

USPC D24/215, 200, 211, 212, 213, 214, 133, D24/107, 231

CPC A61H 7/00; A61H 7/002; A61H 7/003; A61H 7/004; A61H 7/005; A61H 15/00; A61H 2015/0007; A61H 2015/0014; A61H 2015/0042; A61H 23/00; A61H 2023/002

(57) **CLAIM**

The ornamental design for an attachment for massage device as shown and described.

DESCRIPTION

FIG. 1 is a top front isometric view of an attachment for massage device showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom front isometric view thereof.

The broken lines in the figures show portions of the attachment for massage device that form no part of the claimed design.

1 Claim, 5 Drawing Sheets
